HULLER TYPE COTTON GIN

Jeffrey J. Wallace, Amite, La., assignor to Gullett
Gin Company, Amite, La., a corporation of
Louisiana

Application February 28, 1939, Serial No. 259,033

12 Claims.

(Cl. 19—55)

This invention relates to cotton gins, and more particularly to an improved roll dump and breast lift mechanism.

Cotton gins in the past have had relatively awkward means for inspecting the cotton rolls. It has been necessary to manually raise heavy parts of the gin mechanism.

One object of the present invention is to provide an improved cotton gin. Another object is to provide a single mechanism for stopping the ginning operation, and for removing a cotton roll from the cotton box. A further object is to provide a single manually operated mechanism for separating the gin breasts, and for 15 cleaning the gin saws. Yet another object is to provide a gin in which inner and outer breasts may be locked in cooperative position with respect to the gin saws.

A further object is to provide a means for 20 raising the gin breasts away from the ginning saws. Still further objects include the provision of a single manual means for moving the breasts away from the saws, and subsequently moving the breasts relative to each other; manually releasable means for latching the breasts together; unitary means for moving the breasts with respect to the gin frame and for bodily moving the breasts with respect to each other; the provision of means for moving the breasts 25 jointly with respect to the frame and saws, and subsequently moving the breasts relatively with respect to each other and locking the parts in such position.

A still further object of this invention is to 30 provide an improved breast lifting means that in the first movement of the breast lift lever will release the mechanism and raise both the inner and outer breast clear of the saws, then by a further movement of this same lever, lift 35 the second or outer breast clear of the first or inner breast.

Other objects and advantages of this invention will appear from the following description, taken 40 in connection with the accompanying drawings.

In the drawings, wherein like characters represent corresponding parts in the various figures:

Figure 1 is a partial end elevation showing a gin incorporating features of this invention with the parts in position for ginning;

Figure 2 is a similar view showing the gin breasts moved with respect to the gin frame and saws;

Figure 3 is a similar view showing the parts 55 in completely extended position with the gin

breasts moved with respect to the frame, and with respect to each other; and

Figure 4 is a detail view of the operating handle.

Considering the drawings in greater detail, the invention is illustrated by a plurality of end elevation views of a gin, incorporating features of the inventive concept. The internal construction of the gin is not shown, since it is deemed unnecessary for a clear understanding of the 5 invention. However, in this regard the internal arrangement of a cotton gin of the general type contemplated by this invention can be observed in Patent No. 2,142,977.

The drawings illustrate the application of 15 features of this inventive concept to a cotton gin of the air blast type. However, it will be readily understood that the invention is equally applicable to cotton gins of other types. In Figure 1 an end elevation of a gin is shown 20 comprising a frame 10 having an air reservoir 12 and a cotton outlet duct 14 for operation as an air blast gin. A plurality of gin saws 16 are mounted upon a gin saw cylinder, which latter is rotatably supported upon a drive shaft 18. 25 Appropriate power mechanism for driving the gin saws will be provided, but since the details of this mechanism are unimportant insofar as the present invention is concerned, they will not be illustrated in detail. 30

A cotton roll cylinder 20 carrying a series of 35 seed breasts 22 is pivotally supported at 24 upon an upper part of the frame 10. Rotatable end plates 26 are supported in the end walls of the cotton roll chamber or compartment, so as to 40 eliminate or materially reduce any friction between the turning cotton roll and the walls of the roll box. The lower end 28 of the inner breast is provided with a transversely extending runner or brace bar 30 comprising channel 40 member 32 and a wooden insert 34.

At the opposite ends of the foregoing bars and connected to the frame 10 is an appropriate 45 mechanism for absorbing any shocks when the parts are moved together, and for forcibly moving the breasts into extended position when the gin is being opened. This latter mechanism comprises a hollow cylinder 36 which is pivotally secured to the frame by means of a bolt 38. A plunger 40 extends through the cylinder 50 and is pivotally connected to the bar 34 by a lug and pin connection 42 at its one end. The plunger has fixed upon it in spaced relation collars 44 and 46. A heavy spring 48 encircles the plunger and is housed interiorly of the cylinder 55.

der 36 abutting against the collar 34 at one end, and against the apertured flange 50 at the opposite end. When the parts are in the position shown in Fig. 1, the spring is placed under considerable stress. When the breasts are moved away from the gin saws, the collar 46 can move up to an abutting position with respect to the flange 50, and thereby determine the extended movement of the inner breast. This is clearly indicated in Figure 2.

With the parts as thus far described, it will be readily understood that the inner breast 20 is normally positioned as in Figure 1, with the gin saw blade 16 extending through and between breast elements 22. When the parts are released to be moved away from the gin saw blades, the spring 48 moves the inner breast to extended position rotating about the pivot point 24.

The outer breast 52 carries a series of hulling ribs 54 and contains appropriate rotating elements mounted on the shafts 56 and 58 for forcing the cotton bolls or hulls into engagement with the ribs 54 and the gin saws 16, so as to thoroughly break up the hulls and free the cotton and seed therefrom. The upper end of the outer breast is provided with an opening 60 into which the raw cotton is placed, allowing it to fall downwardly in the hulling compartment 62. Any dirt or small parts of the hulls can drop out of the coarse mesh screening 64.

The outer breast 52 is releasably connected to the inner breast when in closed position, by means of a latch 66 which is pivotally mounted at 68 on the inner breast, having a hand grip portion 70 and a latch portion 72 engaging the pin or shaft 74 extending from the outer breast.

The upper end of the outer breast 52 is slidably mounted upon the inner breast by means of a roller bearing comprising a roller 78 pivotally mounted upon the outer breast at 80 and arranged to roll upon the slight upwardly extending track or rail 82. The opposite ends 84 and 86 of the track 82 are arcuate and serve as limit stops for the rollers 78.

45 Manually operated mechanism is provided for moving the inner and outer breasts 20 and 52 together about the pivot 24 with respect to the gin saws. This mechanism comprises the bell-crank shaped lever 88 which is pivoted at 90 upon a boss 92 carried by the outer breast 52. The boss 92 may be a separate member secured upon the outer breast, and is notched for three positions 94, 96 and 98. The bell-crank carries a latch 100 biased by means of a spring 102 into notch engaging position, as shown in Figure 4. To release the manual lever 88 and move it from one position to the other it is merely necessary for an operator to grasp the lever 88, pulling the latch 100 out of engagement with a notch, and 55 moving the lever to another notch engaging position. The lever 88 has a short arm 104 which is pivotally connected at its outer end 106 with a link 108, which latter is pivotally connected to the frame 10 at the point 110.

65 A link bar 112 has an elongated yoke 114 at its outer end, through which the pin 106 extends, and is provided at its inner end with lock collars 116 and 118 at either side of an apertured bracket portion 120 of the frame. A spring 122 70 encircling the rod and interposed between the collar 116 and the flange 120 serves to yieldably hold the rod 112 in one position while determining the degree of movement that the pin 106 may have with respect to the pivot pin 24.

75 The description of the mechanism has been

limited to that shown in the drawings, and is at one end of the gin, it being understood, however, that corresponding mechanism is arranged at the opposite end of the gin, with the exception that the hand lever 88 may preferably be arranged at 5 one end or the other. This eliminates the need of two hand levers, and the mechanism can readily be operated by means of the one lever.

The operation of the gin is substantially as follows: The parts being in the position shown in Figure 1, the normal ginning operations can take place. If it is desired to clear the gin saws for any reason, the manually operated lever 88 is moved from the notch 94 to the notch 96, at which point the parts will be positioned as in Figure 2. In this case, the inner and outer breasts have been forcibly moved away from the gin saw blades 16 as a result of the release of the stress in the spring member 48. In this case the ginning and hulling ribs have been clearly moved away from the gin saw. If it is now desired to remove the cotton roll from the cotton box, the lever 88 is continued in its movement about its pivot, and is latched in notch 98. In this position the parts will be indicated as shown in Figure 3 with the inner and outer breast members being separated to provide a wide passage 124 so that the cotton roll can be quickly and easily removed from the box. During this last movement, the outer breast member 52 is moved bodily with respect to the inner breast member 20, the operator first having released the latch 66 so that the hand lever could move the two breast members relative to each other. During this movement the outer breast member rides on the trackway 82 by means of its rollers 78, and thereby swings the entire outer breast clear of the inner breast. The lever 88 and link 108, as seen in Figure 3, are past dead center position so that the breasts in their outer position are locked against any possible closing. The fact that the latch 100 is also engaged in this position additionally assures the locking of the parts to preclude their possible closing while an operator is inspecting the inner parts of the machine.

It will be observed that at all times when the breasts are open that the spring 48 forces both breasts entirely clear of the gin saws, so that it is physically impossible for an operator to be injured by coming in contact with the saw blades. The spring 48 in its compressed position is of such strength as to exert a force on collar 44 sufficient to raise both the inner and outer breast 20 and 52 from engagement with the saws 16.

Certain features of this application will be found disclosed in my co-pending application Ser. No. 252,633, filed January 24, 1939.

Although a preferred embodiment of this invention has been illustrated and described, variations within the true spirit and scope of the same are to be determined by the appended claims.

What I claim is:

1. A gin breast of the class described including an inner breast member and an outer breast member, a pivot connecting said inner breast member to a gin frame and serving as a common pivot for both breast members, the outer breast member having a rolling upper bearing connection to the inner member, a separable latched connection to the lower part of the inner member, and means constructed and arranged to move said members jointly about said common pivot and to move the outer breast member bodily with respect to the inner breast member.

2. A gin breast of the class described comprising inner and outer breast members, a pivot connecting said inner breast member to a gin frame and serving as a common pivot for both breast members, the outer breast member having a rolling upper bearing connection to the inner member and a lower separable connection to the inner member, and common means constructed and arranged to move said members jointly about said common pivot and to move the outer breast member bodily with respect to the inner breast member.
3. A gin breast of the class described comprising inner and outer breast members, the outer breast member having a rolling upper bearing connection to the inner member and a lower separable connection to the inner member, a pivot connecting said inner breast member to a gin frame and serving as a common pivot for both breast members, and manual means constructed and arranged to move said members jointly about said common pivot and to subsequently move the outer breast member bodily with respect to the inner breast member.
4. A cotton gin comprising a frame, a gin breast of the class described comprising inner and outer breast members, a pivot connecting the inner member to said frame, the outer breast member having a rolling upper bearing connection to the inner member and a lower separable connection to the inner member, and means constructed and arranged to move said members jointly about the pivot on said frame, and to move the outer breast member bodily with respect to the inner breast member.
5. A cotton gin comprising a frame, a gin breast of the class described comprising inner and outer breast members, a pivot connecting the inner member to said frame, the outer breast member having a rolling upper bearing connection to the inner member and a lower separable connection to the inner member, means constructed and arranged to move said members jointly about the pivot on said frame, and to move the outer breast member bodily with respect to the inner breast member, and to lock said members in extended position.
6. A cotton gin comprising a frame, a gin breast of the class described comprising inner and outer breast members, a pivot connecting the inner member to said frame, the outer breast member having a rolling upper bearing connection to the inner member, means constructed and arranged to move said members jointly about the pivot on said frame, and to move the outer breast member bodily with respect to the inner breast member, and to lock said members in extended position, said means being manually releasable to restore the members into cooperative working position.
7. A cotton gin comprising a frame, gin saws mounted in said frame, a gin breast including an inner breast member and an outer breast member, the outer breast member having a rolling upper bearing connection to the inner member, pivot means supporting the inner breast member on the frame, means biasing the members away from the saws, and means constructed and arranged to move said members jointly about the pivot means on the frame away from saws and to move the outer breast member bodily with respect to the inner breast member.
8. In a double ribbed cotton gin a gin breast member having an upper roll box section and a lower ribbed section, a second breast member having an upper roll box section and a lower ribbed section along with a hulling chamber, gin saws normally extending through the ribs on both of said sections, a pivotal mounting on which both sections may be pivoted to clear the ribs on said sections from the gin saws, a track and roller bearing connection between the first and second breast members and means connected to the second breast member to roll the same on its track bearing away from the other breast member, whereby to provide a passage through which a cotton roll in the roll box may be discharged downwardly between the separated members.
9. In a cotton gin, a frame, an inner breast having an upper roll box section and a lower ribbed section, an outer breast having a cooperating upper roll box section and a lower ribbed section, a gin saw cylinder having saws normally extending through the ribs of both of said sections, a fixed upper pivotal mounting for the inner breast on said frame on which the inner breast is directly but revolubly mounted, and around which both of said breasts jointly swing, said breasts being releasably connected at their lower ends, a separate connection including pivoted rollers mounting the outer breast on the inner breast, means pivotally mounted on the outer breast and said frame to effect movement of the breasts relative to each other so as to provide a passage through which a cotton roll in the roll box may be discharged downwardly between the separated breasts, and means constructed and arranged to limit the movement of the outer breast with respect to the frame and to retain the outer breast in extended position.
10. In a cotton gin, a frame, an inner breast having an upper roll box section and a lower ribbed section, an outer breast having a cooperating upper roll box section and a lower ribbed section, a gin saw cylinder having saws normally extending through the ribs of both of said sections, a fixed upper pivotal mounting for the inner breast on said frame on which the inner breast is directly but revolubly mounted, and around which as an axis both of said breasts jointly swing, said breasts being releasably interconnected at their lower ends, a separate connection including pivoted rollers mounting the outer breast on the inner breast, means pivotally mounted on the outer breast and said frame for moving the breasts relative to each other so as to provide a passage through which a cotton roll in the roll box may be discharged downwardly between the separated breasts, means to limit the movement of the outer breast with respect to the frame and to retain the outer breast in extended position, and means responsive to an actuated pivotal means constructed and arranged to thrust the breasts away from the frame and gin saw cylinder.
11. A cotton gin comprising a frame, relatively movable breast members combinedly defining and constituting separable parts of a cotton roll compartment, means constituting a pivotal mount for one member on said frame, means for latching the members in cooperating relation, means for automatically moving the cotton roll compartment forming breast members relatively with respect to the frame and about said pivotal mount thereon, and manual means constructed and arranged to first release the members and allow them to move jointly with respect to the frame and then to move them relative to each other including a lever pivoted on the frame, a bell crank pivoted on the outer breast and to the other end of said lever and manually movable

whereby to permit the automatic movement of said compartment forming breast members, and a roller bearing interconnecting the breast members.

5. 12. A cotton gin comprising a frame, inner and outer breast members, the upper parts of which define a roll box, the inner breast having a pivotal connection with said frame and the outer breast being supported by the inner breast, means biasing said breasts as a unit in a direction to swing said breasts away from said frame about said pivotal connection, manually actuated
- 10

means for normally holding said inner breast closed against the urge of said biasing means, said manually actuated means having an initial movement releasing said biasing means, and including an element thrusting between said breasts for separating them, said element being inert during the initial movement of said manually actuated means, but active to separate said breasts upon further movement of said manually actuated means.

JEFFREY J. WALLACE.
